(57) **CLAIM**

The ornamental design for an inclined photovoltaic assembly, as shown and described.

DESCRIPTION

This is related to our copending U.S. patent application, titled Multiple Position Photovoltaic Assembly, application Ser. No. 10/292,400 and filed on 12 Nov. 2002, the disclosure of which is incorporated by reference.

An inclined photovoltaic assembly made according to the invention is mounted to a roof or other support structure and is used as a source of electrical energy.

FIG. 1 is a top, front, right side isometric view of an inclined photovoltaic assembly showing our new design;

FIG. 2 is a top plan view thereof;

FIG. 3 is a front elevational view thereof;

FIG. 4 is a rear elevational view thereof; and,

FIG. 5 is a right side elevational view thereof, the left side elevational view being a mirror image.
